Primary Examiner — Darlington Ly*Assistant Examiner* — D. Ryan Tisdale(74) *Attorney, Agent, or Firm* — SHUTTLEWORTH & INGERSOLL, PLC; Timothy J. Klima(57) **CLAIM**

The ornamental design for a steering wheel, as shown and described.

DESCRIPTION

FIG. 1 is a front side view of the steering wheel showing our new design;

FIG. 2 is a rear side view thereof;

FIG. 3 is a top perspective view thereof;

FIG. 4 is a bottom perspective view thereof;

FIG. 5 is a left side view thereof;

FIG. 6 is a right side view thereof; and,

FIG. 7 is a front right perspective view thereof.

Any broken lines in the figures illustrate portions of the steering wheel that form no part of the claimed design.
